UNITED STATES PATENT OFFICE.

EBER C. FLINT, OF SAGINAW, MICHIGAN.

BARREL-HOOP MACHINE.

SPECIFICATION forming part of Letters Patent No. 268,395, dated December 5, 1882.

Application filed September 2, 1882. (No model.)

To all whom it may concern:

Be it known that I, EBER C. FLINT, a citizen of the United States of America, residing at Saginaw, in the county of Saginaw and State of Michigan, have invented certain new and useful Improvements in Barrel-Hoop Machines, of which the following is a specification, reference being had therein to the accompanying drawings.

This invention has relation to improvements in machines for cutting barrel-hoops; and it consists in the novel construction and arrangement of the parts, as will be hereinafter described.

The annexed drawings, to which reference is made, fully illustrate my invention, in which—

Figure 1 represents a vertical sectional view of my hoop-machine. Fig. 2 represents a front view of the same, and Fig. 3 is a top or plan view.

The letter A designates two uprights, which are provided on their inner faces with vertical guideways a a, in which slides a frame, B, that carries the knives b b' b', that are operated by a pitman pivoted to the frame and connected to an eccentric secured to a horizontal shaft carrying pinion and gear-wheel, which will be further explained.

C designates the bed-timber, which is secured to the uprights, and is provided on its upper surface with grooves c c, arranged crosswise the same, in which moves a tilting frame, c', that is pivoted at its ends to the bed-timber C. Said bed-timber is also provided on its edge and upper surface, next to the knife-carrying frame, with a transverse groove, c², in which are placed metal strips c³, that are secured in place by means of a wedge, c⁴, driven in rear of said strips.

D indicates a screw-threaded rod, the upper end of which is removably pivoted in bearings d, secured to the center of the tilting frame c', while the lower or opposite end connects with a female threaded head of an adjustable rod, d', that is forked at its lower end, in which is placed a small wheel or roller, d², that is operated upon by a cam, d³, secured to the face of a gear-wheel, d⁴. Said gear-wheel receives its motion from a pinion, d⁵, secured to the horizontal shaft d⁶, that operates the knife-frame aforesaid.

E designates a foot-treadle, hinged at e to the floor, and provided with a lug, e', at its free end, that bears against a spring-pawl, e², that engages the inner edge of the rod d' for the purpose of disengaging the said rod from the cam d³ on the gear-wheel d⁴, and when thus disengaged the foot-treadle is held by its free end by means of a spring-catch, e³, pivoted to the bed-timber aforesaid. Said adjustable rod 60 carrying the roller in its lower end has its forward, backward, and vertical movement in a forked guide-strip, e⁴, secured to the machine, and between the lower end of said rod and the machine-frame is interposed a spring, e⁵, one 65 end of which is secured to said frame, and the opposite end is connected to the roller end of the adjustable headed rod d', thus serving to keep the roller in engagement with the cam d³ while the tilting frame is working. 70

Having thus described the different parts of which my hoop-cutting machine is constructed, I will proceed and explain the manner in which the same is operated.

Power is applied to the horizontal shaft d⁵, 75 which is mounted in suitable bearings, which gives motion to the eccentric f', and by means of the pitman f² the knife-carrying frame receives a vertical or up-and-down movement, carrying therewith the main cutting-knife b and 80 the two lapping-knives b' b', which latter are placed one on each side of the frame, as shown in Fig. 2 of the drawings. The blank strip of wood to be cut or beveled is first pointed and then laid upon the bed-timber C and over the 85 tilting frame c', with the edge to be beveled close to the vertical frame carrying the knives. At the same time the pinion d⁶ gives motion to the gear-wheel, and by its cam d³ operates the adjustable rod d' by said roller traveling upon 90 the cam, and thus tilting the frame at the proper time when the frame is descending with its knives, and thereby causing the plank to be cut and beveled by the main knife b, at the same time the lapping-knives b' b' cut the ends 95 of the strip that forms the lap.

It will be observed that the cam is only part of a circle, and when the tilting frame is not raised, as described, at certain intervals, and the roller escaping, said cam permits the frame 100 c' to lie within the grooves of the bed-timber and flush with surface of the same; also, it

will be observed that by means of the foot-treadle the parts for operating the tilting frame may be disengaged at pleasure by the operator, and the pitch or slant of said tilting frame may be increased or decreased by means of the adjustable rods herein described, thereby enabling the operator to cut any desired bevel on the strip of wood; and, again, by my construction of the bed-timber the strips of metal protect the wear of the edge of said timber next to the knives, and when the hoop leaves the machine to allow another blank to take its place and go through the same operation the hoop is finished.

15 If desired, a gage may be put upon the knife-frame, as shown at *f* in the drawings.

What I claim, and desire to secure by Letters Patent, is—

In a machine for beveling hoops, the combination, with the sliding frame *B*, carrying the main knife *b* and lapping-knives *b' b'*, operated by the pitman *f²*, of the bed-timber *C*, having grooves *c² c²*, wedge *c⁴*, and tilting frame *c'*, the adjustable rod *d'*, screw-threaded rod *D*, foot-lever *E*, spring-pawl *e²*, spring-catch *e³*, cam- 25 gear wheel *d⁴*, meshing with the pinion *d⁵*, eccentric *f'*, having pitman *f²*, by means of which the knife-frame is operated, the whole as described, and for the purpose set forth.

In testimony whereof I affix my signature in presence of two witnesses.

EBER C. FLINT.
